UNITED STATES PATENT OFFICE

2,464,446

CHILD'S SWING

Lester L. Helms, Wingate, N. C.

Application October 1, 1945, Serial No. 619,678

1 Claim. (Cl. 155—65)

1

This invention relates to a swing, and more especially to a swing constructed largely of wood, which is easily assembled, very sturdy, will stand hard usage, is easily adjustable as to height from the ground, and also easily adjustable to accommodate children of various sizes.

It is an object of this invention to provide a swing in which the handle bars and the foot bars can be adjusted vertically with relation to each other and having quickly adjustable takeup means.

It is another object of this invention to provide a swing having a handle bar and a foot bar and means joining the said bars together with a seat member pivoted at one end to the means which join the handle bar and foot bar together, together with a pair of suspending means secured above the handle bar and a single suspension means secured to the free end of the seat member.

Some of the objects of the invention having been stated, other objects will appear as the description proceeds when taken in connection with the accompanying drawings, in which:

Figure 1 is an isometric view of the swing;

Figure 2 is an isometric view of a modified form of the swing;

Figure 3 is an edge view of Figure 2, omitting the seat and the bars to which the seat is attached;

Figure 4 is a cross sectional view taken through the foot bar and the vertical post and being taken near the lower end of Figure 2;

Figure 5 is an enlarged detailed view of the adjustable means shown in Figure 1.

Referring more specifically to the drawings, the numeral 10 indicates a foot bar in Figure 1 having uprising posts 11 and 12, and to the upper end of these posts is suitably secured a handle bar 13. Suitable eye bolts 14 and 15 penetrate the outer ends of the foot bar 10 and the handle bar 13 and suitable nuts (not shown) are disposed on the lower end of these bolts 14 and 15 for securing the two bars 10 and 13 together and binding them against the ends of the bars 11 and 12.

The upper ends of the bolts 14 and 15 have suitable eyes 17 and 18 therein in which suitable rings 19 and 20 are secured, and to these rings 19 and 20 are secured cords 21 and 22. The cords 21 and 22 pass upwardly each through a block 23 and outwardly along the exterior of the block as at 24 and then transversely through the block as at 25, then upwardly and downwardly and being secured to the block as at 26. This forms a loop 27 in which a snap hook 28 is secured so that

the snap hook 28 can be secured to suitable eye bolts 29 which are secured in a ceiling such as 30. There is also disposed a cord 32 which has an identical structure on its upper end and which structure bears like reference characters to that just described.

The lower end of this cord 32 is secured to an eye bolt 33 secured in the outer free end of a seat member 34 which is pivotally connected as by bolt 35 between the bars 11 and 12. It will be noted that the bars 11 and 12 have a plurality of holes such as 36 in which the bolt 35 can be positioned for adjusting the position of the seat member 34 vertically with relation to the main frame portion of the swing.

In Figure 2 a slightly modified form of the invention is shown in which there is a handle bar 40 and a foot bar 41. The foot bar 41 has suitable notches therein which fit over one side of bars 42 and 43, said bars 42 and 43 having a plurality of holes 44 therethrough for receiving a bolt 45 which penetrates one end of a seat member 46, the other end of the seat member having riveted thereto a leaf 47, in the outer end of which is an eye bolt 48 in which a ring 49 is mounted and in this ring is secured a cord 50 whose upper end passes through a ring 51 and through another ring 52 and extends on upwardly through a ring 53 disposed in an eye bolt 54 secured in a ceiling 55.

The free end of the cord 50 is secured to the ring 52 and thus an easy takeup adjustment is provided. The same reference characters apply to the two cords 57 and 58 which have their lower ends secured through rings 59 and 60 which are disposed in the upper ends of eye bolts 61 and 62. These eye bolts have their lower ends threaded and are threadably mounted in tubular bolts 63, 64 which have a bolt 65 threaded into their lower ends which penetrate the foot bar 41. The bar 41 is secured to the upright bars 42 and 43 by means of suitable U-bolts 66 and 67 as is clearly shown in Figure 4. These U-bolts are passed through the foot bar 41 and have each a plate 68 on their free ends with suitable nuts 69 and whereby the bar 41 can be securely clamped to the lower portions of the upright bars 42 and 43 and, thus, by adjusting the telescopic bolts 61, 63, 62, and 64 and securing the bar 41 in adjusted position, the overall height of the frame of the swing can be adjusted to different sizes of children, and the bolt 45 can be placed in any one of the holes 44 and thus, the vertical position of the swing seat 46 can be adjusted.

In the drawings and specification there has been set forth a preferred embodiment of the invention, and although specific terms are employed, they are used in a generic and descriptive sense only, and not for purposes of limitation, the scope of the invention being defined in the claim.

I claim:

A child's swing comprising a pair of vertically disposed, spaced members, a handle bar secured to the upper ends of the spaced members, a foot bar secured to the lower portion of the spaced members and being vertically adjustable relative to the spaced members, a pair of telescopic bolts penetrating the outer ends of the foot bar and the handle bar, the upper ends of the telescopic bolts having eye members therein, a pair of cords secured to the upper ends of the telescopic bolts and having their other ends secured to a suitable support disposed thereabove, the vertically disposed spaced members having a plurality of holes therethrough for receiving a bolt, a seat member having a hole through one end penetrated by said bolt for pivotally mounting

the seat member between the spaced vertically disposed members, the outer end of the seat member having a cord secured thereto, and means for supporting the upper end of the cord at a point above the seat member, said cord having quick takeup means therein comprising an annular member secured in the free end of the cord and through which an intermediate portion of the cord is passed and a second annular member surrounding the first annular member and resting against the cord.

LESTER L. HELMS.
